Primary Examiner — Calvin E Vansant*Assistant Examiner* — Giang Hoang Tran(74) *Attorney, Agent, or Firm* — Taylor English Duma, LLP(57) **CLAIM**

I claim the ornamental design for a bumper guard, as shown and described.

DESCRIPTION

FIG. 1 is a top perspective view of a bumper guard.

FIG. 2 is a first side elevation view thereof.

FIG. 3 is a second side elevation view thereof.

FIG. 4 is a front elevation view thereof.

FIG. 5 is a rear elevation view thereof.

FIG. 6 is a top plan view thereof.

FIG. 7 is a bottom plan view thereof; and,

FIG. 8 is a top plan view thereof showing the bumper guard in a "blank" form or configuration, i.e., in a flattened condition before being formed.

Those features of the bumper guard shown in broken lines form no part of the claimed design. More specifically, the dot-dash lines show unclaimed boundaries of the claimed design and the standard dashed lines show unclaimed environment.
